CLAIM

The ornamental design for a footwear toe cap, as shown and described.

DESCRIPTION

FIG. 1 is a top perspective view of an embodiment of a footwear toe cap showing our design.

FIG. 2 is a right side elevational view thereof.

FIG. 3 is a left side elevational view thereof.

FIG. 4 is a front elevational view thereof; and,

FIG. 5 is a top plan view thereof.

The broken lines are for the purpose of illustrating environmental structure and form no part of the claimed design.
